US0D1094738S

(12) **United States Design Patent** (10) **Patent No.:** **US D1,094,738 S**
Juto (45) **Date of Patent:** **** Sep. 23, 2025**

(54) **MEDICAL STIMULATOR**

(71) Applicant: **Abilion Medical Systems AB**,
Stockholm (SE)

(72) Inventor: **Fredrik Juto**, Stockholm (SE)

(73) Assignee: **Abilion Medical Systems AB**,
Stockholm (SE)

(**) Term: **15 Years**

(21) Appl. No.: **29/891,379**

(22) Filed: **May 4, 2023**

(30) **Foreign Application Priority Data**

Nov. 24, 2022 (EM) 015004232-0001

(51) **LOC (15) Cl.** **24-01**

(57) **CLAIM**

The ornamental design for a medical stimulator, as shown and described.

DESCRIPTION

FIG. 1 is a perspective view of a medical stimulator showing my new design;

FIG. 2 is a top view thereof;

FIG. 3 is a bottom view thereof;

FIG. 4 is a left side view thereof;

FIG. 5 is a right side view thereof;

FIG. 6 is an enlarged front view thereof; and,

FIG. 7 is a rear view thereof.

The equal length broken lines in the photographs depict portions of the medical stimulator that form no part of the claimed design.

1 Claim, 7 Drawing Sheets
